MACHINE FOR APPLYING EDGE BINDINGS
TO SHOE UPPERS

Robert A. Hartt, Lynn, Mass.

Application March 14, 1934, Serial No. 715,516

6 Claims. (Cl. 12—55)

This invention relates to folding machines and more especially to those designed for use in applying a strip of binding, piping, or similar reinforcing or finishing material to the uppers of 5 shoes and to other articles of work in which the edges are bound or finished in a similar manner. Such machines find an especially important use in the manufacture of women's shoes for the application of what is known as "French cord" 10 binding to the edges of the uppers.

According to the customary practice a strip of binding is sewed to the outer margin of the edge portion of a shoe upper, and later is folded over the edge and cemented down. In an earlier application I have shown and described a machine for applying binding of this type which is coated with an adhesive that normally is hard and non-tacky but which is adapted to be rendered tacky by heating to temperatures somewhat above normal. In that machine provision is made for blowing a current of air or other hot gaseous fluid against the coated surface of the binding as the work is fed through the folding instrumentalities, thus making the adhesive on the 20 binding sticky, so that when it is folded over the edge of the upper or other article of work and is pressed down, it will be securely held in place by the adhesive. Such a procedure avoids the 25 necessity for applying cement during the folding operation and thus substantially eliminates any danger of damaging the work due to the accidental application of cement to those portions of the upper which are to be exposed, or which, for any other reason, should not be cemented. The invention disclosed in said application has proved commercially valuable and has gone into substantial practical use. The present invention aims further to improve and perfect mechanisms of this general character, although it is contemplated that the invention 30 may also be used in other folding machines.

In equipping folding machines with apparatus for supplying hot air to them for the purposes above mentioned, it has been customary either to 45 use a main supply of hot air piped to a series of machines, or else to use a separate air supplying apparatus for each individual machine, the latter practice being more common than the former. In either arrangement a continuous stream 50 or jet of hot air is delivered to the folding instrumentalities, no provision being made for controlling the delivery of air or other gaseous fluid in accordance with variations in the requirements of the machine or of the work. For the best 55 results the adhesive coating on the binding should

be heated to a certain optimum temperature where it is sticky and plastic but still is not entirely fluid. In prior arrangements, however, during the periods in which the operator is changing from one piece of work to another, or for any other reason is not using the machine, the discharge of hot air continues and heats up the folding devices to such a high temperature that when she puts a piece of work into the machine she is very likely to burn her fingers. Or she may find 10 that the parts have been so overheated that the adhesive on the binding will be rendered too fluid to give the best results. In addition, the supply of hot air required by the work varies with the rate at which the machine is operating and 15 is considerably greater when the machine is running at a high speed than when it is slowed down for some reason, as for example, in turning a corner or doing a difficult portion of the work. A further objection to prior arrangements of the 20 type in which air supplying apparatus is used individual to the respective machines has been that such apparatus is in the way and is the cause of considerable annoyance.

The present invention deals especially with 25 these conditions and it aims to devise a thoroughly practical solution for the problem presented by them.

The nature of the invention will be readily understood from the following description when 30 read in connection with the accompanying drawings, and the novel features will be particularly pointed out in the appended claims.

In the drawings,

Figure 1 is a perspective view of a common 35 commercial form of folding machine equipped with apparatus embodying features of this invention;

Fig. 2 is a perspective view of parts of the machine at the folding point;

Fig. 3 is a plan view, partly in section, of an 40 attachment for supplying hot air organized in accordance with this invention;

Fig. 4 is a vertical, sectional view, partly in elevation, showing the fan and adjacent parts 45 of the attachment shown in Fig. 3;

Fig. 5 is an end view of part of said attachment showing, in vertical section, the devices for mounting it on the machine; and

Fig. 6 is a perspective view, partly in section, 50 of an article of work produced in the machine.

The drawings show the invention applied to a rotary folding machine of a common commercial construction, this machine being designed especially for applying the so-called "French cord" 55

binding to the uppers of shoes and other kinds of work which can be handled in essentially the same manner. As above stated, the usual practice is to stitch the binding strip 2, Fig. 6, to the 5 edge of the part 3 of the upper, or equivalent article of work, and later to fold the unattached margin of the binding over the edge of the upper and to press it down upon the margin of the upper, substantially as shown in Fig. 6. Prior to 10 performing this folding operation, however, the coating of meltable adhesive carried by the inner surface of the binding strip is softened so that when the binding is folded over and pressed down it will be held securely in its folded position.

15 The machine shown includes a driven feed wheel 5, which serves both to support and feed the work, and a rotary head 6 carrying a series of folding disks 7 which not only revolve with the head but are also positively rotated on their 20 own axes. A guide block 8 is positioned adjacent to the wheel 5 and head 6 and is provided with an angular guiding surface across which the work is fed on its way to the folding disks. As the binding travels across the guide block 8 it 25 is pressed into the angle of the guiding face by a small roll or wheel 9, Fig. 2, having a toothed edge, the wheel being supported for yielding movement toward and from the guide block.

So far as these features are concerned the machine shown is of the common commercial construction. It will be observed that the axis of 30 the rotary head 6 is located diagonally with reference to that of the feed wheel 5, the arrangement being such that as the work is fed across 35 the guide block 8, the binding 2 is bent or folded upwardly at approximately right angles to and across the edge of the section 3 of the shoe upper, and as it passes out of engagement with the upright guiding surface of the block, it is engaged by the disks 7 and wiped forward over the 40 margin of the upper. The disks press it down into substantially the position shown in Fig. 6. The inner surface of the binding is coated with the adhesive, and a current of air or other hot 45 gaseous fluid is directed through the tube 10 and against the coating of adhesive while the binding is moving across the face of the guide block so that it softens the adhesive and makes it sticky before it is folded over by the wipers 7.

50 The attachment provided by this invention for supplying hot air comprises a small fan or blower 12, mounted in a tapered casing 13, this casing being connected by a tube or conduit 14 with the casing 15 of a heater unit to which the small 55 discharge tube 10 is secured. Located in the latter casing is an electric heating unit 16, through and around which the current of air created by the fan 12 is forced, this unit being of such a size as to heat the current of air to approximately the desired temperature. While this 60 temperature can vary considerably, a temperature of from approximately 160° to 180° F. of the air issuing from the end of the discharge tube 10 will produce satisfactory results under ordinary working conditions. It should be understood, however, that the temperature of the air required necessarily will vary with the nature of the adhesive, and consequently, some variation may be found with different makes of bindings. Preferably the heating unit 16 is removably supported entirely from its upper end in the casing 15, the insulator being of a reticulated or foraminous form so that a very free flow of air around the resistance wire occurs. This casing 65 is removably secured to the conduit section 70

14 as by screws 17-11, and the latter section is similarly secured by screws 18-18 to the end of the casing 13.

The fan or blower is mounted on a shaft 20 5 which is supported in two bearings, one carried by the removable perforated end plate 21 of the casing and the other by the bearing arm 22 that is secured to said end plate. Preferably a stationary baffle plate 23 is secured in the casing in axial alignment with the fan where it serves 10 to direct forwardly the air propelled by the fan and to prevent the rotation of any substantial body of air with the fan.

For the purpose of driving this fan, a friction wheel 24 is secured fast to the shaft 20 at a 15 point between the bearings for this shaft, and it is arranged to engage the periphery of the fly wheel 25 of the folding machine and to be driven by it. In the particular machine shown the fly wheel 25 normally is engaged by a brake 26 and 20 is held against rotation. It is provided, however, with a cone clutch face arranged to engage a similar face on the constantly driven idle pulley 27 which runs on the same shaft with the fly wheel 25 but is loosely mounted on said shaft. 25 This pulley is grooved to receive a driving belt 28 which, as shown, usually runs through the table and is driven from a pulley 29 which may either be mounted on a counter shaft driven by an electric motor 30 or may be connected to 30 power in any other convenient manner. Mounted immediately below the pulley 27 is a rocker 31 which carries the brake 26 and also supports a cam arm 32. This rocker is connected through 35 mechanism, not shown, but which is a regular part of the machine, to a chain 33, the lower end of which is fastened to an arm 34 projecting from a treadle 35.

The arrangement is such that when the treadle 40 is depressed the rocker 31 is swung toward the observer, Fig. 1, thus releasing the brake 26 from the fly wheel 25 and swinging the cam-shaped end of the arm 32 across and into contact with the usual "button" 36 on the end of the pulley 27. This movement forces the pulley 27 toward 45 the left and into driving engagement with the fly wheel 25, thus operating through the driving connections in the machine to revolve the feed wheel 5 and the folder head 6. It should be understood that the parts 25, 26, 27, and 31 50 to 35, inclusive, and the connections between them, are all standard parts of the particular folding machine shown and are not parts provided by this invention. The friction wheel 24 preferably is held constantly in engagement with the fly wheel 25, so that as soon as the latter begins to revolve it starts up the fan 12 and thus 55 forces air through the casing 13, conduit 14 and the heater unit to the work, this air being heated immediately prior to its delivery. The delivery 60 of hot air to the work, therefore, starts simultaneously with the starting of the machine. Furthermore, since the heater 16 is located closely adjacent to the point at which the air is discharged, it keeps the tube 10 continuously heated, 65 and some air flows slowly by convection through the tube 10 and the heater back into the conduit 14, and sometimes also into the casing 13. A supply of hot air thus is always available, even when the machine is idle, and the current of air 70 directed against the work when the machine starts up is heated to the desired temperature and is delivered instantly upon the starting of the machine without any intervening delivery of cool air. The flow of hot air stops instantly 75

when the machine is stopped due to the fact that the fly wheel 25 stops.

With this arrangement, therefore, the supply of hot air is controlled jointly with the operation of the machine, both being governed by the manual movement of the treadle 35. The air supplying apparatus thus is operated only when it is needed. In addition, the fact that the fan or blower 12 is driven from the fly wheel 25 and its speed consequently varies with the speed of operation of the machine, provides for the variation of the delivery of hot air to the work in accordance with variations in the requirements of the work. In other words, if the operator slows down the machine for any reason, as for example, in turning a difficult corner, the rate of discharge of air to the work is automatically reduced during this period in which less air is required, but the supply is increased again when the machine speeds up. A better operating condition thus is maintained.

For the purpose of operatively supporting the air supplying apparatus, the casing 15 is removably secured to the machine frame by a metal strap 36, Fig. 1, and the fan casing 13 is mounted on a bracket mechanism which also is removable. This bracket structure is best shown in Figs. 1 and 5. It comprises a U-shaped member 37, adapted to straddle the top of the casing, with its legs fitting snugly against the opposite sides of the machine frame and releasably secured to said frame by two screws, one of which is shown at 38, and the other being secured similarly to the machine. Pivoted to this member 37 is a small bracket 40 having an upright arm that is screwed securely to and supports the fan casing 13. A leaf spring 41, Fig. 5, is secured to this bracket and bears on the top of the U-shaped member where it tends to hold the friction wheel 24 out of contact with the fly wheel 25. A screw 42 is threaded through the horizontal arm of the bracket 40 and into the member 38, so that by turning this screw in or out, the contact of the friction wheel 24 with the surface of the fly wheel 25 may be adjusted. This adjustment can be made while the blower is running, if desired. Such mounting of the parts provides for the convenient attachment or removal of the air supplying apparatus. At the same time this apparatus is so constructed that it occupies relatively little space, is out of the way, it leaves the table room unencumbered, and it requires a minimum of attention on the part of the machine operator.

The invention therefore effectually overcomes the various difficulties above described while providing an arrangement which can be manufactured and installed more economically, is cheaper to operate, and is more convenient to use.

While I have herein shown and described a typical embodiment of my invention, it will be understood that the construction shown has been designed with particular reference to the requirements of the individual folding machine illustrated in the drawings, and that some changes in the construction, mounting and driving of the attachment may be required in adapting it to other makes of machines, while still retaining the essential characteristics of the illustrated embodiment of the invention. Consequently, the invention may be embodied in a variety of forms without departing from the spirit or scope thereof. Also, in the particular machine shown the fan and the machine start and stop together. It is contemplated, however, that it may be desirable in some installations to make the fan start slight-

ly in advance of the machine while still retaining the simplicity of control of the arrangement shown. This can be done in several ways, as for example by mounting the friction pulley on the outside of the outer bearing 22 where it can be driven by the pulley 27, allowing the casing 13 to swing on its pivot and connecting it with the treadle 35 so that the first part of the depressing movement of the treadle will bring the friction wheel into contact with the pulley 27 and will initiate the flow of hot air slightly before starting the machine into operation. These and other changes can be made within the spirit and scope of the invention.

The treadle 43 and its connections through the belt crank lever 44 and chain 45 are those with which the machine commonly is equipped for raising and lowering the feed wheel 5.

Having thus described my invention, what I desire to claim as new is:

1. In a folding machine, the combination with folding instrumentalities, of means for directing a current of hot gaseous fluid against the portion of the work to be operated upon, said means including a fan, and mechanism for driving said fan comprising a driving element common to both the fan and the machine and a constantly driven member for driving said element, and means for starting and stopping the operation of said element by said member.

2. In a folding machine, the combination with folding instrumentalities, of means for directing a current of hot gaseous fluid against the portion of the work to be operated upon, said means including a fan, and mechanism for driving said fan comprising a driving element common to both the fan and the machine and a constantly driven member for driving said element, and a single controlling device for starting and stopping the operation of said element by said member.

3. In a folding machine, the combination with folding instrumentalities, of means for directing a current of hot gaseous fluid against the portion of the work to be operated upon, and means for controlling the delivery of said hot gaseous fluid to the work substantially in accordance with variations in the speed at which the work is operated upon.

4. In a folding machine, the combination with folding instrumentalities, of means for directing a current of hot air against the portion of the work to be operated upon; said means including power driven apparatus for creating a confined flow of air, means for heating said air, and means for conducting the heated air to the point of discharge; and additional means for controlling the delivery of said air to the work substantially in accordance with variations in the requirements of the work.

5. In a folding machine, the combination with folding instrumentalities, of means for directing a current of hot air against the portion of the work to be operated upon; said means including power driven apparatus for creating a confined flow of air and means for heating said air; said means being constructed and arranged to hold a supply of hot air closely adjacent to the point of discharge and in readiness for delivery during the period in which the apparatus is not in operation, and means under the constant control of the operator for starting said delivery of air to the work instantly.

6. In a folding machine, the combination with folding instrumentalities, of means for directing

a current of hot air against the portion of the work to be operated upon; said means including power driven apparatus for creating a confined flow of air and means for heating said air; said 5 means being constructed and arranged to maintain a supply of heated air ready for instant delivery to the work but in such a condition that

delivery to the normal working position is prevented, a treadle, and connections arranged to be operated by said treadle for effecting such delivery, when desired, without an intervening delivery of cool air to the work.

ROBERT A. HARRIT.
